UNITED STATES PATENT OFFICE.

THOMAS B. MOATS, OF BUCYRUS, OHIO.

REMOVABLE-TOP CONTINUOUS KILN.

Application filed June 9, 1921. Serial No. 476,296.

To all whom it may concern:

Be it known that I, THOMAS B. MOATS, a citizen of the United States, residing at Bucyrus, in the county of Crawford and 5 State of Ohio, have invented a new and useful Removable-Top Continuous Kiln, of which the following is a specification.

This invention relates to kilns, the primary object of the invention being to provide a kiln having a removable top or crown whereby the kiln may be emptied or filled from a point exteriorly thereof.

A further object of the invention is to provide a crown constructed of a plurality 15 of interlocking blocks formed of fire clay or the like.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 20 within the scope of what is claimed, without departing from the spirit of the invention.

Referring to the drawings:—

Figure 1 is a transverse sectional view 30 through a kiln constructed in accordance with the present invention.

Figure 2 is a fragmental plan view of the kiln.

Figure 3 is a fragmental side elevational 35 view of the kiln.

Figure 4 is an enlarged detail view disclosing the means for connecting the frame work of the crown, to the fire clay bricks.

Referring to the drawings in detail, the 40 kiln is of the usual construction as far as the base or body portion thereof is concerned, and is shown as provided with the usual fireboxes 5 which communicate with the smoke stacks through the ducts 6 and 45 passageways 7.

Heat is directed to the interior of the kiln in the usual manner, as through the passageways 8 disposed in the opposite sides of the kiln and formed in the side walls 9 50 thereof.

The upper inner surfaces of the walls 9 of the kiln are inclined as at 10 to conform to the inclined surfaces 11 of the crown 12,

so that when the crown is positioned on the side walls 9, the inclined edges of the crown 55 12 will contact with the inclined edges 10 causing the crown to be properly seated on the kiln walls in a manner to prevent lateral movement thereof.

The crown 12 which forms an important 60 feature of the invention, is formed of a plurality of curved supporting beams 13 which have right angled extremities adapted to rest on the upper edges of the side walls 9 of the kiln. The supporting beams 13 are 65 arranged in spaced relation with each other throughout the length of the kiln, and have connection with the longitudinally disposed eye beams 14 which are supported in spaced relation transversely of the crown 12. 70

These I beams 14 provide supports for the fire clay blocks 15, each of which being provided with a groove of a shape to conform to the contour of an I beam, so that the fire clay blocks may be positioned on the 75 I beam.

Each block 15 is provided with a lateral groove 16 formed in one side face thereof, there being provided a tongue 17 extending from the opposite side face thereof, the 80 tongue 17 being designed to fit within the groove 16 of the adjacent block 15, when the blocks are positioned on the I beams of the crown.

The blocks 15 are also formed with reinforcing walls 18 which connect the side walls of the blocks, strengthening the side walls of the blocks and rendering the same capable of withstanding the strain directed thereto by the weight of the adjacent block. 85

From the foregoing it will be seen that a crown constructed in accordance with the present invention, may be readily and easily removed by connecting a crane thereto, it being understood that the top is to be removed in sections, the crane having connection with the sections in any suitable manner whereupon the oven may be readily filled from the top thereof. 90

When the oven has been filled, it is obvious that the crane may be operated to return the crown to its normal position. 100

Having thus described the invention, what is claimed as new is:—

A kiln including side walls having the 105 upper inner surfaces thereof inclined, a

crown comprising curved supporting beams, I beams having connection with the curved supporting beams, a plurality of blocks having grooves to accommodate the I beams, 5 to support the block, and said blocks having lateral tongues and grooves, whereby adjacent blocks may be interlocked.

In testimony that I claim the foregoing as my own, I have hereto affixed my signature in the presence of two witnesses.

THOMAS B. MOATS.
